CLAIM

The ornamental design for a cuff saver, as shown and described.

DESCRIPTION

FIG. 1 is a top, front and left side isometric view of a cuff saver showing my new design, where the broken line showing of the shoe is for illustrative purposes only and forms no part of the claimed design;

FIG. 2 is a front, top and left side isometric view thereof;

FIG. 3 is a top elevational view thereof;

FIG. 4 is a front elevational view thereof;

FIG. 5 is a left side elevational view thereof the right side being a mirror image;

FIG. 6 is a bottom elevational view thereof; and,

FIG. 7 is a rear elevational view thereof.
